SANITARY FOOD PACKAGE

Application filed July 23, 1930. Serial No. 469,940.

This invention relates to the packaging of food products in general, including amongst other things such bakery products as pies, cakes, etc., but it also includes such food products as meats, specially prepared products, etc.

The invention has an especial application, however, in connection with bakery products, where the practice heretofore has been somewhat insanitary, and where there is an increasing demand for better means and methods of packaging, especially for pies, cakes and the like, for the purpose of keeping them cleaner and fresher, and also for the purpose of packaging them in a manner that is pleasing and attractive to the eye.

For instance, in the usual manner of handling pies, cakes, etc., after same are baked, they are subject to a fair amount of handling, not only in the bakery proper, but also during transportation to the retail stores, and also during the process of distribution in the latter to the ultimate consumers. Though these pies, cakes, etc., are often placed in plates, this is the only protection afforded, and the dust and dirt is permitted to accumulate on them, which is especially objectionable in various kinds of pies having a soft surface, as the dust collects upon and clings to the latter particularly. Besides, though the plate protects the bottom of the pie, the top is exposed and it dries out faster than if properly sealed all over.

The object of this invention is to completely eliminate the above objections, and to package the food commodity at the earliest possible moment, in an entirely sanitary and attractive manner, so as to exclude all dirt and dust therefrom during the handling, and until it reaches the ultimate consumer, and also to more effectively preserve its freshness up to the time of consumption. The drawing illustrates one form of our invention, but the latter is subject to change and variation within the scope of the appended claims, without departing from the spirit of our invention.

Fig. 1 is a front view of one form of our invention, this view being partly in section and partly in full.

Fig. 2 is a front view of another form of

our invention showing a modified feature not illustrated in Fig. 1.

Fig. 3 is a view looking at the bottom of our package as illustrated in Fig. 2, the view being in direction of the arrows X³ in Fig. 2. 55

Fig. 4 illustrates one form of covering member used in our invention.

Fig. 5 illustrates a modified form of covering member used in our invention.

Figs. 6 and 7 illustrate minor modifications that will be more fully described later. 60

Although the drawing, and the following description, refers to a pie as the food product packaged, this is only by way of example, and it is understood that any other item of food can be substituted for the pie, all within the terms of this invention. 65

Fig. 1 illustrates the pie 1 having the usual crust portion 2 and body portion 3, this pie however being only meagerly and diagrammatically illustrated, all immaterial details being omitted. 70

Underlying this pie is a plate 4 having the usual bottom portion 5, side wall portion 6, and flange portion 7. 75

Over this pie, and for the purpose of excluding dust, dirt, moisture and air circulation therefrom, we add a covering member 8, the perimeter of which is sealed and fastened to the plate so as to form a dust-proof enclosure in which the pie is located, between said plate and the covering member 8. 80

It is obvious, the pie, plate and covering member, when arranged as above, forms a neat substantial package convenient for handling, and since the pie is packaged in this manner at the earliest proper moment after baking, and with practically no manual handling prior to that time, it is also obvious that this package delivers the pie finally to the ultimate consumer in the most sanitary possible condition free from accumulated dust and dirt, and also free from any possible insect taint, or human taint through handling. 85 90

Although the shape of the package when viewed from above, or from below, may be of any desired form, for instance rectangular, elliptical, or round, the usual custom is to make same round as indicated in the partial view thereof in Fig. 3. 95 100

In making a neat proper seal between the perimeter of the covering member 8 and the perimeter of the plate, we have found it desirable but not essential that there should be slits 9, or 9' cut at intervals around the perimeter of the covering member 8 as generally indicated in Fig. 4. Slits 9 are just straight cuts, with no material removed, whereas slits 9' are triangular in shape, a small portion of the material having been removed. The latter form of slit permits a slightly neater seal on the plate than the former, but the former is a little more economical to cut because it permits the use of cheaper cutting tools. Although Fig. 4 shows half the slits of one form, and the other half of another form, it is of course understood that in practice only one type of slit (or none at all) is used all around the covering member, and the particular type that is selected, and its distribution or direction around the perimeter of the covering member, can be varied even beyond the types that we have illustrated in the drawing, without departing from the spirit of this invention.

With the slits thus cut around the perimeter, all crinkling is eliminated, and the tongues 10 between the slits lie nice and flat against the perimeter of the plate as indicated in Fig. 3.

For the purpose of sealing and causing the perimeter of the covering member to stick to the perimeter of the plate, the glue or adhesive used, is of course carefully selected so as not to be objectionable in a chemical or sanitary sense, even if some of it should come in contact with the food product, but of course every provision is taken during the process of packaging to make certain that none of the adhesive comes in contact with the pie, or other food product. To illustrate this we might add, with reference to the type of package illustrated in Fig. 1 for instance, that after the pie is put in the plate, the adhesive may in some way be applied all around the bottom of flange 7 of the plate, as by causing the latter to roll around on some narrow rollers diagrammatically indicated by dotted lines at 11. These rollers could dip into fluid adhesive 12 in containers 13, also diagrammatically indicated by only dotted lines, and with this arrangement it is obvious that the adhesive will be neatly and evenly applied all around the bottom of flange 7 as the plate turns around on these rollers 11, without permitting any of the adhesive to get up onto the food product in the plate. The covering member 8, preferably with no adhesive on it anywhere, could then be placed centrally over the plate and food product, and the edge of this covering member could then be folded neatly around and under the perimeter of the plate, being permanently sealed by the adhesive on the plate. When handled this way, it is certain that none of

the adhesive comes in contact with the pie, but this mode of applying the adhesive is cited by way of illustration only, and is not cited as a limitation on this invention, as it is understood that the adhesive could be successfully applied in other ways.

Fig. 5 illustrates a modification of the covering member, which we will now describe. The dotted lines 14 indicate the edge of the sheet material from which the covering members are cut, two of these covering members 15 being shown approximately in their relative positions as they are respectively cut from the sheet. In order to save some of this sheet material that would otherwise be wasted, and to use it for a good and helpful purpose in connection with the package, we call attention that instead of cutting the external contour of the covering member entirely circular all around as illustrated in Fig. 4, this contour can be cut in such manner that at certain places 16 the radial distance to the center 17 is greater than the radial distance of the remaining contour 18. This gives short tongues 10 corresponding to tongues 10 in Fig. 4, and also long tongues 10' at places 16. The purpose of these long tongues 10' is clearly illustrated in Figs. 2 and 3, showing that whereas the short tongues 10 merely underlie the flange 7, these long tongues 10' pass downward along the side wall portion 6 of the plate. Obviously, this gives a still tighter and firmer hold of the covering member onto the plate 4, and since these extra long tongues 10' are procured from the otherwise wasted material, the benefit of the tighter and more secure seal which they give, is obviously helpful. As indicated in Fig. 5, the shape of the slits 19, separating these long tongues 10', is preferably such that the tongues make even and exact contact with each other not only along the flange portion 7 of the plate, but also along the side wall portion 6 thereof, as illustrated in Figs. 2 and 3.

In making the covering member 8, a wide variety of materials can be selected, preference being given to such qualities as render them dust-proof, moisture-proof, air-proof, germ-proof, and also preferably transparent as the latter quality greatly improves the appearance and attractiveness of the package by rendering the pie or other food product entirely visible, even though same is securely sealed for sanitary and other reasons. The particular selection however we leave entirely to the judgment and desires of the user or maker of such packages, who may depart as widely as he desires from the preferences which we have just expressed, without departing from the spirit of our invention. We prefer however a covering material that is entirely transparent, or as nearly so as possible, and also one that is substantially air and moisture-proof, as well as germ and

dirt-proof, as all this helps protect and preserve the freshness of the food product, as well as its cleanliness, and other good qualities. If waxed or paraffined paper is used, 5 instead of other transparent substitutes, then the use of glue or other adhesive for attaching the covering member to the plate, as above described, can be dispensed with, and a suitable heating element can be used for heating 10 the wax and paraffine to cause the latter to attach and fasten the edges of the covering member to the plate.

The partial views of our package, as shown in Figs. 6 and 7 illustrate modifications of 15 the flanged portion 7 of the plate, as illustrated in Fig. 1. Fig. 6 illustrates this flanged portion as being curved in some form such as 7', instead of being flat like in Fig. 1, and Fig. 7 shows this flanged portion of the 20 plate being entirely omitted. However, all these modifications, and others, are wholly within the spirit of our invention.

In conclusion, the gist of this invention resides in the fact that the covering member 8 25 overlying the food article and plate member 4, has its perimetral portion tucked around and beyond the perimetral edge of the plate member, so that the perimetral portion of the covering member is in fact fastened to the 30 opposite surface of the plate member from that on which the food article rests. The importance of this is that the adhesive (or other fastening expedient) used for fastening the cover and plate members together, is not applied to the same surface of the plate as that 35 which the food article rests upon, but is applied to the opposite surface of the plate member, i. e., the surface beyond the perimetral edge of the plate, thereby very considerably 40 reducing the likelihood that the adhesive or equivalent expedient will come in contact with the food. In other types of packages where the covering member is made to adhere to the same surface of the plate 45 member as the food article rests upon, the likelihood of the adhesive coming into contact with the food article is considerably larger than in our invention, and this distinction is an important feature of our invention.

50 From the previous description it is of course understood that the pie plate 4 may be of the usual paper or other suitable composition commonly used for this purpose in the trade.

We claim:

55 1. A sanitary food package comprising an article of food having an approximately round exterior contour, a round plate underlying the same and having a bottom portion, also a frusto-conical side wall portion 60 rising from said bottom portion, and also a flange portion extending outwardly from the top of said frusto-conical side wall portion to form the perimeter of said plate, and a dust-excluding covering member having a curved 65 exterior contour, some portions of said con-

tour lying radially further than others from the center of said covering member, said covering member having slits cut therein around the perimeter thereof, and the perimeter portion of said covering member between said slits being fastened to said plate, said radially further portions of said covering member being fastened along the exterior of said frusto-conical side wall portions of said plate, to make a neat sanitary package holding said article of food in a substantially dust-proof enclosure between said plate and said covering member. 70 75

2. A sanitary food package comprising a food article, a plate member underlying same and formed of relatively thin material terminating in a perimetral edge that divides said plate material into two surfaces upon one of which surfaces, or a part thereof, said food article rests, and the other of which surfaces may for distinction be termed the opposite surface of said plate member, and a dust-excluding covering member having slits cut at intervals therein around its perimeter, said dust-excluding covering member over-lying said food article and plate member, and the slitted perimetral portion of said covering member being tucked around said perimetral edge of the plate member and being fastened to said opposite surface of said plate member in the vicinity of said perimetral edge. 80 85 90 95

3. A sanitary food package comprising a food article, a plate member underlying same and formed of relatively thin material terminating in a perimetral edge that divides said plate member into two surfaces upon one of which surfaces, or a part thereof, said food article rests, and the other of which surfaces may for distinction be termed the opposite surface of said plate member, and a dust excluding covering member overlying said food article and plate member, the perimetral portion of said covering member being tucked around the said perimetral edge of the plate member and being fastened to said opposite surface of said plate member. 100 105 110

In testimony whereof, we have executed these presents this 17th day of July, 1930.
